GOLF BAG

John K. Hotze, St. Louis, Mo.

Application November 19, 1932, Serial No. 643,349

19 Claims. (Cl. 150—1.5)

This invention relates to certain new and useful improvements on golf bags and pertains more particularly to a reinforcement for the carrying means of the bag and to the bag wall as well.

5 Another object of the invention is in providing the bag with improved reinforcing means to which the lifting or carrying straps of the bag are secured, for preventing distortion of the bag during carrying of the bag when the bag is laden 10 with playing clubs.

A further object of the invention is in providing the carrying reinforcement which is secured to the bag wall, with resilient inlays which are cooperable with the reinforcement.

15 The invention is also a furthering of the improvements in a golf bag disclosed in my pending application Ser. No. 538,157.

Other and further objects will appear in the specification and be specifically pointed out in the 20 appended claims, reference being had to the accompanying drawing exemplifying the invention, and in which:

Figure 1 is a side elevation of a golf bag showing the invention applied thereto, a lower portion 25 of the golf bag being broken away.

Figure 2 is an enlarged fragmentary longitudinal section taken approximately on the line II—II of Fig. 1.

Figure 3 is an enlarged transverse section taken 30 approximately on the line III—III of Fig. 2.

Figure 4 is an under side view of the reinforcing structure before being applied to the golf bag wall.

Figure 5 is an enlarged fragmentary cross section taken approximately on the line V—V of Fig. 1.

In the accompanying drawing, 1 designates a golf bag having a bag wall 2, a base 3 secured to the bag wall and a collar 4 secured to the opposite ends of the bag wall at the open end or mouth 5 of the bag.

40 A reinforcing structure 6 of the an approximate Y-shape which may be made of one piece, if desired, but in the instance of this disclosure, 45 the reinforcing structure is built up and comprise a material length 7 which may be of heavy leather or other suitable material, having a pair of branching portions 8 diverging from one end and secured thereto by stitching.

50 Secured to each branching portion 8, by respective rivets 9, is a metallic resilient strip 10 and on each side of each strip 10 in opposing position, is a pair of elongated apertures 11. Extending longitudinally of the length or leg 7 and 55 secured thereto at its ends by rivets 12, is a flat

metallic resilient strip 13, the strips 10 and 13 being secured on the under side of the branching portions 8 and the leg 7 as shown in the several figures of the drawing.

5 The reinforcing structure comprising the parts 7 and 8 and their respective resilient strips 10 and 13 is secured to the bag wall 2 in Y-shaped formation by stitching, designated at 14 and 15, as shown in Fig. 1, the upper end 16 of the leg 7 being inserted under the collar 4 adjacent the bag mouth by transverse stitching 18.

Prior to stitching, the branching portions 8 to the bag wall, inverted U-shaped strips 19 are engaged in opposing pairs of apertures 11 of said branching members, and the feet 20 of each member 19 will be engaged and held in position by the stitching 15 when the branching portions 8 are secured to the bag wall.

15 Each member 19 when secured to respective branching portions 8 provides loops for over-engaging respective straps 21, each of said straps at one end being secured to the extending end of respective branching portions 8 either by stitching or riveting, the opposite ends of said straps being secured to a D link 22.

20 A carrying handle 23 is secured at its upper end to the leg 7 by providing an aperture 24 in said leg and the upper end of the handle being inserted in the aperture and secured to the leg, and the lower extending end of the handle 23 being secured to the D link 22.

25 Connected to the lower end of the handle 23 by a buckle 25, is one end of a carrying strap 26, said strap being secured at its upper end to the D link 27 which is fastened to the bag adjacent 30 the mouth thereof.

35 From an inspection of Figs. 1, 2 and 3, it is to be noted that the branching portions 8 extend around the bag girth to points adjacent the under carrying side 23 of the bag wall, and when the golf bag is carried in a customary inclined position with the playing clubs therein, the weight of the laden bag will be received by the strap 26 which is mounted over the shoulder of the golfer or caddy.

40 As the branching portions 8 are secured to the bag wall intermediate of its length, the laden weight will be received by the branching portions 8 and the lifting force will be thrust forwardly and upwardly through the branching portions, to 45 the leg 7 with which they connect and to the collar 4 of the bag mouth, the reinforcing structure 6 resisting the load. This forward and upward thrust of the load is brought about by the shoulder carrying strap being connected at its lower 50 55

end to the pair of straps 21 through the D link 22 and said straps 21 being connected at their lower ends to respective branching portions 8, the straps 21 and the lifting strap 26 therefore receiving 5 and carrying the load from the lower side 28 of the bag which is carrying the load.

Also, by reason of the branching portions 8 and the leg 7 with which they connect being secured to the bag wall throughout their entire length, 10 and the branching portions 8 extending around the bag girth to the lower side 28 of the bag, a more even distribution of the carrying load is presented to the reinforcing structure and the stiffeners or resilient metallic strips 11 and 13 of the 15 branching portions 8 and the leg 7 respectively of the structure 6, will prevent buckling of the bag wall from a point intermediate the bag length to the mouth 5 of the bag.

The resilient metallic strips 11 of the branching 20 portions 8, by reason of their being flat when secured to said branching portions as shown in Fig. 4, will obviously present an outward thrusting force to the branching portions when said portions are secured to the bag wall, said metallic strips 11 therefore tending to hold the circular shape of the bag, and thus prevent sagging of the bag.

For holding the straps 21 in conforming contact with the branching portions 8 during carrying of the bag, the loops formed by the members 30 19 are provided, said loops preventing the straps at their upper ends from pulling away from the branching portions 8 during carrying of the loaded bag.

35 The handle 23, while not being ordinarily used in carrying a loaded golf bag, is however, capable of directing the carrying strains to the reinforcing structure 6 when the handle is used as a lifting member by reason of it being secured at one end to the straps 21 and at its opposite end to the leg 7 of the reinforcing structure.

This improved reinforcing structure when applied to a golf bag, not only reinforces the bag wall for carrying purposes and for cooperation 45 with the bag wall for eliminating distortion, but the structure also provides a golf bag of durability, fitness and refinement.

Obviously, constructional modifications of the 50 device are possible without departing from the spirit of the present invention and therefore it is to be understood that it is not necessary to limit the invention by the terms used in the foregoing description, excepting such as as the state of the art may require.

55 What I claim is:—

1. A golf bag having a reinforcing structure secured to the bag wall comprising a longitudinally disposed leg extending from adjacent the bag mouth and diverging portions leading from said leg, a carrying strap having branches secured to each of said portions, and a retaining member secured to each diverging portion having engagement with respective strap branches.

2. A golf bag having a reinforcing structure secured to the bag wall comprising a longitudinally disposed leg extending from adjacent the bag mouth and diverging portions leading from said leg, a carrying strap having branches secured to each of said portions, and a retaining member secured to each diverging portion over-engaging respective strap branches for permitting sliding movement of said strap branches thereunder.

3. A golf bag having a reinforcing structure secured to the bag wall comprising a longitudinally disposed leg extending from adjacent the bag 75

mouth and diverging portions leading from said leg, a carrying strap having branches secured to the extending end of each of said diverging portions, and a retaining member secured to each diverging portion over-engaging respective strap branches intermediate their ends. 5

4. A golf bag having a reinforcing structure secured to the bag wall comprising a stiffening leg having a pair of diverging portions extending from one end, a resilient member bearing against 10 each of said diverging portions and held in lengthwise position thereto, and carrying means for the bag connected to said diverging portions.

5. A golf bag having a reinforcing structure secured to the bag wall comprising a stiffening leg having a pair of diverging portions extending from one end, a resilient member disposed lengthwise of each diverging portion and fixed so as to resiliently bear thereagainst, and carrying means for the bag connected to said diverging portions 20 adjacent their extending ends.

6. A golf bag having a reinforcing structure secured to the bag wall comprising a stiffening leg having a pair of diverging portions extending from one end, a flat resilient member secured at 25 one end to each diverging portion and adapted to bear thereagainst, and carrying means for the bag connected to said diverging portions adjacent their extending ends.

7. A golf bag having a reinforcing structure 30 secured to the bag wall comprising a longitudinally disposed leg and diverging portions leading from said leg at one end, resilient means effective on each of said diverging portions and said leg, said resilient means being disposed lengthwise of 35 said diverging portions and said leg and interposed therebetween and the bag wall, and a carrying strap secured to the extending end of each diverging portion.

8. A golf bag having a reinforcing leg secured 40 to the bag wall extending from the mouth of the bag and having a pair of diverging portions extending partially around the girth of the bag wall and secured thereto, a resilient member interposed between each of said diverging portions 45 and the bag wall, and carrying means secured to the ends of said diverging portions.

9. A golf bag having a reinforcing leg secured to the bag wall extending from the mouth of the bag and having a pair of diverging portions extending partially around the girth of the bag wall and secured thereto, a resilient member interposed between each of said diverging portions, said leg and the bag wall, and carrying 50 means secured to the ends of said diverging portions.

10. A golf bag having a reinforcing leg secured to the bag wall extending from the mouth of the bag and having a pair of diverging portions extending partially around the girth of the bag 60 wall intermediate of its length, a carrying strap having branches secured to the end of each of said diverging portions, and retaining means co-operable with each of said strap branches for holding them against said portions.

11. A golf bag having a reinforcing structure secured to the bag wall comprising a longitudinally disposed leg extending from adjacent the bag mouth, diverging portions leading from said leg to portions of the bag wall girth adjacent the 70 center of the bag wall length, a carrying strap having branches secured to each of said portions, and a retaining member secured to each diverging portion cooperable to retain the strap branches against respective diverging portions. 75

12. A golf bag having a reinforcing structure secured to the bag wall comprising a stiffening leg having a pair of diverging portions extending from one end, a longitudinally disposed resilient member secured to and active on each of said diverging portions, a carrying strap having branching connection with the extending end of each of said diverging portions, and a retaining member secured to each diverging portion at a distance from their ends through which respective branching connections of said carrying strap are under-engaged.
13. A golf bag having a reinforcing structure secured to the bag wall, diverging resilient means forming part of the structure extending around the bag wall girth, and carrying means for the bag having branches secured to the structure adjacent the extending end of each of said diverging resilient means.
14. A golf bag having a reinforcing structure secured to the bag wall, diverging flat resilient strips forming part of the structure extending around the bag wall girth, and carrying means for the bag having branches secured to the structure adjacent the extending end of each of said resilient strips.
15. A golf bag having a reinforcing structure comprising a longitudinally disposed flat resilient strip extending from adjacent the bag mouth towards an intermediate portion of the bag wall length, a pair of flat resilient strips disposed divergently from one another and from the extending end of said other resilient strip, and carrying means having a pair of branches at one end, each being secured to the bag wall adjacent the extending ends of said diverging strips, the other end of said carrying means being secured to the bag at or adjacent the mouth thereof.
16. A golf bag having carrying means secured at one end to the bag adjacent the mouth thereof, the other end of the carrying means branching to different points of the bag wall girth adjacent the center of the bag length, bag wall stiffening means partially encircling a portion of the bag wall to which the girth engaging points of the carrying means are secured, and a cooperable retaining member over-engaging each branching part of the carrying means.
17. A golf bag having both a handle and a carrying strap, the handle having its upper end directly secured to the bag and its lower end free of the bag, and a pair of diverging extensions secured to and leading from the lower end of the handle, secured to the bag at their extending ends and being free of the bag from their points of securance thereto, and retaining means over-engaging each extension.
18. A golf bag having both a handle and a carrying strap, the handle having its upper end directly secured to the bag and having its lower end indirectly secured to the bag through a pair of intervening diverging extensions, and retaining means over-engaging each extension.
19. A handle for a golf bag having one end free of the bag, a pair of diverging extensions leading from the free end of the handle, said extensions encircling a portion of the bag girth and being secured thereto at their extending ends, the other end of said handle being directly secured to the bag, and a retaining member for each extension over-engaging a respective strap.

JOHN K. HOTZE.
